CONNECTER

William G. Fotsch, Chicago, Ill., assignor to Reliable Electric Co., Chicago, Ill., a corporation of Illinois

Application August 4, 1934, Serial No. 738,471

6 Claims. (Cl. 173—263)

My invention relates to electrical connectors and more particularly to a connector adapted for clamping two electrical conductors together, for example, where it is desired to connect a branch line to a main line conductor.

In devices of this character, it is particularly advantageous to have a connector that consists of only one piece so that the workmen do not have difficulty in assembling two or more elements with the wire. These connectors are often used where the workman is working on a line some distance above the ground, and, with the branch conductor, the main conductor, and the clamp, he has considerable difficulty if the clamp consists of two or more parts that he must assemble in order to make the connection.

My invention contemplates also the provision of a clamp of this character wherein the parts may be made up of stampings so as to reduce the cost of the clamp without sacrificing any of its advantages.

My invention further contemplates provision of a clamp of this character in which the clamp can be positioned on an unbroken conductor and aligned with the conductor to receive a tap or branch conductor with a single motion.

Other and more specific objects and advantages of the invention will appear as the description proceeds in connection with the accompanying drawing wherein the preferred form of the invention is shown. It is to be understood, however, that the drawing and description are illustrative only and are not to be taken as limiting the invention except in so far as it is limited by the claims.

In the drawing—

Fig. 1 is an elevation showing the connector in position clamping a tap or branch conductor to a main line conductor;

Fig. 2 is a plan view looking up at Fig. 1; Fig. 3 is a section on the line 3—3 of Fig. 1.

Fig. 4 is a view like Fig. 1, but showing the manner in which the conductor enters the clamp; Fig. 5 is an elevation taken at right angles to Fig. 4.

Referring now in detail to the drawing, the connector is made up of a shell piece 5, a slotted or U-shaped support 6 for the wire, and the clamping screw 7. The clamping screw 7 screws threads into the top of the shell 5 and is swivelled to the wire support 6 so that the three elements cannot become separated, and they thus form a substantially one-piece connector. The shell 5 is preferably stamped from sheet metal

of the requisite thickness and has the lips 8 and 9 at opposite sides thereof which form rests for supporting and strengthening elements for receiving the line conductors 10 and for providing spaced supports therefor.

The wire support 6 is made up from a partly round strip which, in cross section, is of the shape indicated at 6a in Fig. 2. This strip is bent to U-shape as shown best in Fig. 3 and is slightly flattened at the base as indicated at 11 to form a bearing for the squared end 12 of the screw 7. The screw 7 is provided with an extension 13 which passes through an opening in the base of the wire support 6 and is flattened in the countersunk portion 14 so as to permanently connect the members 6 and 7 together so that 7 may rotate with respect to 6. The shell 5 is cut from the open end to provide the opposed curved walls at 15 and 16 through which the unbroken conductor 10 can be inserted, it being understood that there are two of the passages directly opposite each other defined by the edges such as 15 and 16.

This construction provides a pair of oppositely directed hook portions 17 and 18 which are reinforced by the portions 8 and 9 to form spaced supports receiving the conductors 10.

When the conductor 10 is inserted, it is in the position shown in Fig. 4 with respect to the clamp, and it is evident that, by merely pushing the conductor 10 into the clamp, the shell 5 must turn with respect to the conductor so that it revolves about one-fourth of a complete turn. The conductor 10 is then positioned across the two hook portions 17 and 18 in position to have the branch line conductor 20 inserted through the shell and the wire supporting member 6 over it. After that, it is only necessary to turn the screw 7 to force the wire support 6 down, and the two wires are clamped tightly together between the spaced supports 17 and 18 on one side and the base of the member 6 on the other side.

This is a particularly good clamping action as it is mechanically strong due to the tendency to bend or kink the conductors between the three points of pressure, and the conductors are in contact over a considerable limit so as to give a good electrical connection.

In assembling these connectors, the screw 7 is turned back to the full of its movement away from the hooks 17 and 18, and, in this position, the U-shaped wire support 6 is turned to the position shown in Fig. 4, that is, so that the slot through the member 6 is at right angles to its ul-

timate position when the wire 10 is seated on the hooks 17 and 18. With the screw 7 tightened in this position, the wire support 6 will remain there so that the mouth of the connector is open 5 to directly receive the main line conductor 10, and the camming action of the edges 15 and 16, particularly the edges 15, will turn the wire support with the wire 10 relative to the shell 5 and thus properly align the wire support to receive 10 the branch wire 20 and at the same time loosens the screw 7 since the member 6 turns in the direction to advance this screw. The shell is preferably cut out as indicated at 21 and 22 to provide a small receiving notch for the wire 20. 15

15 When the connector is tightened on the two wires 10 and 20, it is substantially locked in assembled position since the bottom wire cannot rotate in the hooks 17 and 18, and, in addition, the slight spring or bend imparted to the wire 20 acts after the fashion of a lock spring to prevent the turning of the screw 7.

The U-shaped wire support also performs an important function where one or both of the conductors being clamped together may be of the 25 stranded wire type. With such conductors, the strands tend to open or spread apart when pressure is applied. The wire support, which supplies the pressure in this clamp, holds the strands at the sides and thus prevents their spreading. 30 From the above description, it is believed that the construction and operation of this device will be clear to those skilled in this art and the advantages thereof readily apparent.

Having thus described my invention, what I 35 claim as new and desire to secure by Letters Patent is:

1. A connector of the character described, having a cup-like shell, opposed slots in the wall of said shell to receive a conductor placed transversely of said shell, said slots being directed from the open end of the shell towards the other end thereof and spirally about the shell, and at their inner ends having portions extending toward the open end of the shell to seat a conductor inserted therein, and a U-shaped support telescoping with said shell and secured thereto, said support being adjustable endwise relative to the shell to clamp conductors, wires, cables or the like therebetween. 40
- 45 2. A connector of the character described, consisting of a shell, opposed slots in the wall of said shell to receive a conductor, wire, cable or the like, placed transversely of said shell, said slots being directed from the open end of the shell toward the other end thereof and spirally about the shell, and having extending end portions directed to receive and seat a conductor, wire, cable, or the like, and a U-shaped jaw telescoping with said shell and secured thereto by means 50

adapted to move said jaw longitudinally of said shell.

3. A connector of the character described, consisting of a cup shaped shell, slots directed from the open end of said shell to receive a conductor, 5 wire, cable, or the like placed therein, the edge portions of said slots forming a seat for said conductor, receiving and fastening means for a second conductor connecting said second conductor to said first conductor, said receiving and fastening means consisting of a slotted support telescoping said shell and rotatable in said shell to align the slot therein with the conductor seats in said shell and adjustable endwise of said shell to clamp said conductors, wires, cables, or the 10 like therebetween and means for adjusting said support endwise of said shell. 15

4. A connector consisting of a body having therein a pair of opposed elongated slots for holding a conductor or a plurality of conductors 20 in parallel relation, said body having oppositely located conductor guide slots extending from one end of said body into the sides of said holding slots, and a clamping member rotatable in said body to align it with said holding slots, and adjustable endwise of said body to clamp conductors tightly in said holding slots, means to adjust said clamping member endwise of said body while it is aligned with said holding slots, said clamping member having side portions to engage the 30 conductors and prevent their spreading between the holding slots. 25

5. A connector consisting of a body having therein a pair of opposed elongated slots for holding a conductor or a plurality of conductors 35 in parallel relation, said body having oppositely located conductor guide slots extending from one end of said body into the sides of said holding slots, and a clamping member rotatable in said body to align it with said holding slots, and adjustable endwise of said body to clamp conductors tightly in said holding slots, means to adjust said clamping member endwise of said body while it is aligned with said holding slots, said clamping member having means to close said 40 guide slots when it is clamped against conductors in said holding slots. 45

6. A connector of the character described comprising an outer shell having one end open, said shell having slots extending into the walls thereof from said open end to receive a conductor placed transversely of said shell, an inner support having a seat for said conductor, said inner support being rotatably mounted and adjustable axially in said shell, means to adjust said support 50 axially in said shell, and seating means in the wall of said shell for said conductor consisting of oppositely directed hook shaped portions in the edges of the slots in said shell. 55
